UNITED STATES PATENT OFFICE.

RAYMOND E. McKEE, OF CHICAGO, ILLINOIS.

DESIGN FOR A COIN-HOLDER.

45,944.

Specification for Design.

Patented June 16, 1914.

Application filed March 4, 1914. Serial No. 822,520. Term of patent 7 years.

To all whom it may concern:

Be it known that I, RAYMOND E. McKEE, a citizen of the United States, residing at Chicago, in the county of Cook and State of Illinois, have invented a new, original, and ornamental Design for Coin-Holders, of which the following is a specification, reference being had to the accompanying drawing, forming part thereof.

The Figures 1 and 3 illustrate side views of my coin holder. Fig. 2 illustrates a front view and Fig. 4 a plan view.

I claim:

The ornamental design for a coin holder, as shown.

RAYMOND E. McKEE.

Witnesses:

HARRY L. SHAVER,

FRANK J. SCHROEDER, Jr.
